APPARATUS AND METHOD FOR THE REGULATION OF OPERATIONS IN TREATMENT OF FLUID MATERIALS

Harrison S. Coe, Palo Alto, Calif.

Application June 28, 1932, Serial No. 619,714

6 Claims. (Cl. 83—9)

This invention relates generally to systems and apparatus for the treatment or handling of fluid material, and to methods utilized in the same. It has particular application to systems including a classifier, for the treatment of comminuted solids together with a liquid component to effect a size separation, where it is desirable to maintain or establish certain desired conditions of operation.

10 It is an object of the invention to devise a means and method for amplifying slight changes in density of a fluid material, thereby making available ample power for operating various mechanisms.

15 It is a further object of the invention to provide an improved system and method, characterized by the use of a classifier and ball mill in closed circuit relationship, which will facilitate the maintenance of a proper operation of the classifier.

20 A further object is to provide an improved system and method, characterized by the use of a classifier and ball mill in close circuit relationship, which will facilitate proper feed of fresh material to the ball mill.

25 A further object of the invention is to provide an improved means and method which will indicate the character of the load upon a classifier.

Further objects of the invention will appear 30 from the following description, in which the preferred embodiments of my invention have been set forth in detail in conjunction with the accompanying drawings.

Referring to the drawings:

35 Figure 1 is a plan view, illustrating apparatus incorporating the present invention.

Fig. 2 is a side elevational view in cross section, illustrating the apparatus shown in Fig. 1.

40 Fig. 3 is a side elevational view in cross section, partly diagrammatic, illustrating a further apparatus incorporating the present invention.

Fig. 4 is a cross sectional detail taken along the line 4—4 of Fig. 3.

45 Fig. 5 is a side elevational view in cross section, partly diagrammatic, illustrating certain features of the invention applied to the automatic control of a ball mill feeder.

Fig. 6 is a diagrammatic view illustrating a complete system incorporating the apparatus of 50 Figs. 1 to 5 inclusive.

Fig. 7 is a side elevational view in cross section, partly diagrammatic, illustrating the specific gravity and amplifying means of Figs. 1 and 2 applied directly to the material within a classifier.

55 Fig. 8 is a side elevational view in cross sec-

tion, partly diagrammatic, illustrating certain features of my invention as applied to a cone classifier.

Referring first to Figs. 1 and 2 of the drawings, the apparatus illustrated therein consists of 5 a structure 9 forming inflow and outflow launders 10 and 11. An upright partition 12 serves to split the material supplied to the inflow launder 10, so that a part of this material flows thru the by-pass 13, and another part flows thru certain portions 10 of a specific gravity testing means.

The part of the fluid material which does not pass thru bypass 13, is caused to flow downwardly thru a conduit 14, the upper end of which communicates thru the bottom wall of structure 9. 15 A lateral conduit 16, connects the lower end of conduit 14, with the lower end of another upright conduit 17. The upper end of conduit 17 communicates thru the bottom wall of the outflow launder 11. Material discharged from conduit 17 20 is caused to flow over a wier 18, to maintain the height of material within conduit 17 substantially constant.

In conjunction with the parts described above, there is a structure designated generally at 19, 25 which is formed to afford a liquid receptacle 21. A horizontal partition 22, serves to define a liquid receiver 23 above the reservoir 21. Structure 19 is likewise formed to provide an auxiliary liquid receptacle 24, the lower portion of which is 30 in communication with receptacle 21 thru an orifice 26. To enable a flow of liquid into auxiliary receptacle 24, from a source under substantially constant head, receiver 23 is shown provided with a compartment 27, the lower portion 35 of which is in communication with a pipe 28 leading to the auxiliary receptacle 24. An overflow pipe 29, leading from compartment 27, is adapted to discharge into the outflow launder 11.

Extending downwardly within the conduit 17, 40 there is a conduit or pipe 30, having a lower open end, and having its upper end communicating with the lower portion of the auxiliary receptacle 24. As will be presently explained, liquid 45 continuously introduced into the auxiliary receptacle 24, flows downwardly thru pipe 30, to establish a hydrostatic balance with the material in conduit 17, at a point located at the lower open end of pipe 30. Assuming that a continual flow of liquid occurs into receptacle 24 from pipe 28, the level of liquid within this receptacle, and within the receptacle 21, will vary in accordance with variations in the gravity of material in conduit 17. To translate such variations into mechanical movement, I provide a float 31 within 50 55

receptacle 21. Float 31 is operably connected to one end of a counterbalanced lever 32, this lever having a fixed fulcrum 33. In order to amplify movements of lever 32, thus affording considerable power for purposes to be presently explained, I provide means including a liquid chamber 34, which can be likewise formed as a part of structure 19. Chamber 34 is provided with a lower fixed discharge orifice 36. For introducing various quantities of liquid into chamber 34 from receiver 23, I provide a pipe 37 which is controlled by a movable valve member 38. This valve member is connected to the counterbalance lever 32 so as to be opened and closed by movements of the same. Chamber 23 is adapted to receive flow of liquid at a constant rate from a suitable source, such as is represented by the water pipe 39. Positioned within container 34, there is another float 41, which can be connected to the member or mechanical contrivance to be operated in accordance with changes of the gravity of material in conduit 17. In this particular instance float 41 is shown connected to one end of a counterbalancing lever 42, which in turn is operably connected to a valve 43 in a water flow pipe 44.

Operation of the apparatus illustrated in Figs. 1 and 2 is as follows:—Assuming that the fluid material supplied to the inflow launder 10 consists of solid particles together with one or more liquid components, a part of this material will flow directly to the outflow launder 11 thru bypass 13, and another part will flow downwardly thru conduit 14, thru conduit 16, and upwardly thru conduit 17 to the outflow launder. A substantially constant height will be maintained between the lower end of pipe 30, and the upper surface of material in conduit 17, assuming that a constant stream of water is being introduced into receiver 23, from pipe 39. Liquid within receiver 23 will overflow into compartment 27, and from this compartment, flow will occur thru overflow pipe 29, and thru pipe 28 at a constant rate to the auxiliary receptacle 24. The liquid within receptacle 24 will seek such a level that the column, as measured from the surface of liquid in receptacle 24 to the lower open end of pipe 30, will exactly balance the hydrostatic pressure of the material within the conduit 17 at that point. Because of the communication of receptacles 21 and 24, thru orifice 26, liquid in receptacle 21 will tend to seek the same level as the liquid in receptacle 24. Assuming now that the gravity of fluid material flowing thru the apparatus increases, a greater head of water within pipe 30 and receiver 24, will be required to maintain a hydrostatic balance at the lower end of pipe 30. Therefore for a time continual downflow of water thru pipe 30 will cease, until the level of liquid within receptacle 24 has raised to a height sufficient to reestablish the hydrostatic balance. Conversely if the gravity of fluid material decreases below a given value, the downward flow of water thru pipe 30 will be momentarily accelerated, until a hydrostatic balance at the lower end of pipe 30, is again established. This will result in a lowering of the level of liquid in receiver 24.

The level of liquid within receiver 24 will tend to fluctuate rapidly, particularly when the flow of material thru conduit 17 is not uniform. However the level of liquid within reservoir 21 will not fluctuate rapidly, but will vary gradually so as to in effect represent a mean level 75 for the rapid varying levels within receiver 24.

Assuming now that the density of the fluid material increases above a given value, so as to raise the level of liquid in receptacle 21, float 31 is raised, thus causing movement of valve member 38 toward open position. An increased flow 5 of water therefore occurs from receiver 23, to the chamber 34, which results in a substantial increase in the head of liquid maintained above orifice 36, thus causing float 41 to raise to operate lever 42 and valve 43. Conversely if the 10 gravity of fluid material decreases, to cause a fall in the level of liquid in reservoir 21, float 31 causes valve member 38 to move toward closed position, thus decreasing the rate of flow of water into reservoir 34. Such a decreased flow is 15 accompanied by a lowering of the level of liquid within container 34, so that float 41 causes movement of valve 43 in an opposite direction.

With respect to the functioning of float 41 in conjunction with container 34, it should be noted 20 that the rate of flow thru orifice 36 is determined by the head of water maintained above this orifice. This head will vary responsive to variations in the rate of flow of liquid into container 34, assuming that the variations all occur above 25 a range sufficient to maintain a column of liquid above orifice 36. It is therefore obvious that float 41 will move thru a relatively wide range, for variations in the rate of flow of water into container 34. Likewise it is also apparent that float 30 41 can be caused to move thru a relatively wide amplitude compared to float 31, and forces of high magnitude can be exerted by this float dependent upon its size.

The apparatus described above, and the method 35 utilized in the same, can be applied to the control and regulation of various other equipment. One specific application of great value, is in conjunction with a classifier of the drag type. In such an application the overflow from the drag type 40 classifier is delivered to the launder 10 while the discharge of water from pipe 44, controlled by valve 43, is introduced into the classifier together with the feed of fluid material thereto. Assuming now that the gravity of the overflow from 45 the drag type classifier tends to increase above an optimum desired value, valve 43 is automatically adjusted to permit a greater quantity of water or other diluting liquid to be discharged into the classifier together with the fluid feed. 50 Such an increased flow of water into the classifier tends to effect a compensating control to reduce the gravity of the overflow to the desired optimum value. Correspondingly a decrease in the gravity of the overflow below the optimum desired value, causes an automatic adjustment of 55 valve 43, to decrease the rate of flow of water to the classifier together with the fluid feed thereto. The net result, in such a system, is to maintain the gravity of the overflow substantially constant 60 between predetermined limits.

Figs. 3 and 4 indicate an apparatus incorporating certain novel features of my invention, as applied directly to a drag type classifier. In this case I have shown a liquid receptacle 51, having 65 its lower portion in communication with another liquid receptacle 52, thru the orifice 53 (Fig. 4). A pipe 54 is connected to receptacle 51, and has its lower open end terminating within the classifier 56. Classifier 56 is of the drag type, being 70 provided with an oscillating rake 57, and an overflow launder 58. The lower end of pipe 54 terminates at an intermediate point substantially below the wier 59, over which the overflow discharges into launder 58. Arranged within recep- 75

tacle 52, there is a float 61 connected with a counterbalance lever 62. This lever is in turn shown connected to a small valve 63, to regulate flow of water or other liquid thru pipe 64. As an example of indicating means, float 61 is also shown connected to a pivoted pointer 66 associated with graduated scale 67. The receptacle 51, is adapted to receive water or other suitable liquid at a constant rate from a suitable source, 10 as for example a water pipe 68.

In operating the apparatus described with reference to Figs. 3 and 4, the water column in pipe 54, will establish a hydrostatic balance at the point 69, at the lower open end of this pipe. The 15 hydrostatic pressure at point 69 will of course depend upon the average density of the zone of material within the classifier, above point 69. Any variation of density will of course result in a re-establishment of the hydrostatic balance at 20 point 69, by variation of the level of water within reservoir 51.

I have discovered that with the lower end of pipe 54 properly positioned within the classifier, and with the classifier operating at optimum 25 capacity, the water in reservoir 51 will seek a corresponding level, which will be indicated by pointer 66. In the event the classifier is over-loaded, a zone of material in the classifier of considerably greater density, than the density of 30 the overflow, rises above the level of the lower end of pipe 54, thus causing the level of water in reservoir 51 to rise accordingly to re-establish a hydrostatic balance at point 69. By noting this condition, as indicated by pointer 66, or as indicated by the position of float 61 or the level of liquid in reservoir 51, the operator can immediately take steps to reduce the feed to the classifier, to re-establish proper operating conditions.

If desired the response secured by the apparatus of Figs. 3 and 4, can be employed to automatically regulate the load to the classifier. In this event the stream of water automatically controlled by valve 63, is utilized to operate amplifying means, which in turn directly regulates the feed to the classifier. An arrangement of this character is illustrated in Fig. 5, where the amplifying means regulates the feed of material to a ball mill, which in turn feeds the classifier. Thus in this case a movable gate 70, controls 50 discharge of crushed ore or like material, from the chute 71 associated with hopper 12. The discharge from chute 71 is delivered to an endless conveyor 73, which delivers the material to the feed hopper of a ball mill. The amplifying means 55 for operating gate 70 consists of a container 74 having a lower discharge orifice 76. This container receives the stream of water from pipe 64 which is controlled by valve 63 (Fig. 3). In order to move gate 70 in accordance with the position- 60 ing of receptacle 74, this gate is shown carried by a pair of pivoted arms 77 and 78. Arm 77 is fixed with respect to an arm 79, upon which receptacle 74 is suspended. The gate 70 can be of sufficient weight to normally urge it towards closed position when there is no water in container 74.

It is evident that with the arrangement described above with reference to Fig. 5, variations in the rate of flow thru pipe 64 to container 74, by virtue of automatic regulation of valve 63 (Fig. 3) makes available ample power for automatically adjusting gate 70. Thus a decrease in the rate of water flow to container 74, responsive to an increase in effective gravity to which the apparatus of Fig. 3 is responsive, serves to 75 close gate 70 and reduce the supply of material.

In Fig. 6 I have shown a complete system which includes both means for automatically controlling introduction of water into the classifier together with the feed, in response to changes in the gravity of the overflow, and which also incorporates means for automatically adjusting the feed to the classifier, to prevent overloading of the same. The classifier in this case is indicated generally at A, the apparatus of Figs. 1 and 2 is indicated at B, the apparatus of Figs. 3 and 4 10 is indicated at C, and the amplifying means incorporated in Fig. 5 at D. E represents feed means to the ball mill F and is represented as being automatically controlled by the amplifying means D. Ball mill F is shown in closed circuit relationship with the 15 classifier A, that is the heavier coarse material removed from the classifier is returned to the ball mill F thru line 1, and after being retreated in the ball mill, is returned in part to the classifier as by line 2. Water pipe 44 is controlled by a valve 20 43 and is shown connected with the feed line 2 from the ball mill. Water pipe line 64, controlled by valve 63, leads to the amplifying means D, and serves to automatically regulate the feed to 25 the ball mill F.

With the system described above with reference to Fig. 6, the apparatus C, by automatically regulating valve 63, serves thru the instrumentality of amplifying means D, to automatically regulate the feed to the ball mill F, and thus 30 to automatically regulate the feed to the classifier A. In other words if the load upon the classifier increases above an optimum desired value, the feed of fresh material to the ball mill is automatically decreased to gradually reduce the load, 35 and thus return the classifier to optimum operating conditions. Likewise the apparatus B, by automatically regulating valve 43, serves to maintain density of the overflow substantially constant, and makes possible optimum setting conditions within the classifier under proper conditions of load.

As shown in Fig. 7, it is possible to utilize the specific gravity testing means and amplifying means of Figs. 1 and 2, to act directly upon the 45 material within a drag type classifier. Thus in this case pipe 30 extends directly into the classifier, and water pipe 44 is connected to the classifier feed pipe 2. With such an arrangement the dilution of the feed is automatically controlled in 50 accordance with the average density of the zone of material above the lower end of pipe 30.

As shown in Fig. 8, certain features of the invention can also be applied to the control of a cone type classifier. In this case the cone classifier 86, is provided with a flexible underflow discharge conduit 87, such as a rubber hose. Adjacent the lower end of the cone, there is an auxiliary discharge conduit 88 leading to the upright conduit 14 of specific gravity testing means. 60 This testing means is similar to that incorporated in Figs. 1 and 2, except that the auxiliary receptacle 24 is omitted, and pipe 30 connects directly with receptacle 21. The amplifying means in this case serves to automatically regulate the 65 main discharge thru conduit 87. Thus conduit 87 is adapted to be pinched between a fixed abutment 89 and a roller 91. Roller 91 is carried by one end of a lever 92, biased by weight 93 in a direction to close conduit 87. Suspended by 70 lever 92, there is a receptacle 94 having a lower fixed orifice 96. Pipe 97, leading from pipe 37 of the specific gravity testing means, discharges into receptacle 94.

With the apparatus of Fig. 8, a portion of the 75

underflow from the cone classifier is continually tested, and the density indication secured is amplified to automatically control the rate of discharge, thus tending to maintain the density of the discharge substantially constant. In the event the gravity tends to increase, the quantity of water in receptacle 94 increases to permit a greater rate of discharge thru conduit 87. Conversely if the density decreases below a desired value the quantity of water in receptacle 94 decreases, thus causing hose 87 to be collapsed a greater amount between abutment 89 and roller 91.

I claim:

1. In a method of the class described characterized by the use of a material classifier together with a ball mill in closed circuit relationship, securing an indication of the load upon the classifier by determining the effective fluid head required, at a fixed point within the mass of material in the classifier, to effect a hydrostatic balance with respect to said material, simultaneously continually testing the specific gravity of the overflow discharged from the classifier, adjusting the feed to the ball mill in accordance with said indication, introducing a stream of diluting liquor into the classifier together with the feed from the ball mill, and varying the flow of said diluting liquor in accordance with variations in the gravity of the overflow from the classifier.

2. In apparatus of the character described, a classifier, a ball mill arranged in closed circuit relationship with the classifier, whereby the ball mill delivers liquid feed to the classifier and the classifier is arranged to deliver coarse material therefrom back to the ball mill, means for introducing diluting liquid into the classifier together with the feed from the ball mill, means operating responsive to changes in the gravity of the overflow from the classifier for automatically regulating said introduction of diluting liquid, means for regulating the feed of fresh material to the ball mill, and means responsive to variations of the average density within an upper zone of predetermined depth within the classifier for automatically adjusting said feed means.

3. In apparatus of the class described, a container having a lower discharge orifice, means independent of said orifice for introducing a stream of liquid into said container whereby liquid being introduced into the container may simultaneously flow out of the container through said orifice under the gravity head thereby established within the container, a classifying ap-

paratus, means actuated by variations in the quantity of liquid within said container for modifying operation of said classifying apparatus, and specific gravity testing apparatus, associated with said classifying apparatus and serving to control the rate of flow of liquid into said container.

4. In apparatus of the class described, a receptacle adapted to receive a stream of liquid, a pipe communicating with said receptacle and adapted to extend downwardly into a mass of fluid material of varying gravity, the lower end of said pipe being open, valve means adapted to be controlled by the level of liquid within said receptacle, a container provided with a lower orifice for gravity flow of liquid from the container, means independent of said orifice and controlled by said valve means for introducing a varying stream of liquid into said container whereby liquid being introduced into the container may simultaneously flow out of the container through said orifice under the gravity head of said liquid thereby established within the container, and actuating means actuated in accordance with variations in the quantity of liquid within said container for modifying the gravity of said mass of fluid material.

5. In apparatus of the class described for handling material consisting of a liquid component together with solids, a cone type classifier adapted to receive said material, continuously operating specific gravity testing means operating upon the underflow discharge from said cone, and means responsive to said specific gravity testing means for increasing the rate of discharge of underflow from said cone when the specific gravity of the underflow increases, and for decreasing the rate of discharge of underflow from said cone when the specific gravity of said underflow decreases.

6. In apparatus of the class described, a container having a fixed lower discharge orifice, means independent of said orifice for introducing a stream of liquid into said container whereby an outflow of said liquid is maintained by gravity flow through said orifice simultaneously with introduction of said liquid into the container, continuously operating specific gravity testing means adapted to act upon a body of fluid material of varying gravity and serving to regulate the rate of flow of said stream, and means actuated in response to variations in the quantity of liquid within the container for modifying the gravity of the fluid material acted upon by said testing means.

HARRISON S. COE. 55
